[57] CLAIM

The ornamental design for a vehicle tire, substantially as shown and described.

DESCRIPTION

FIG. 1 is a perspective view of a vehicle tire showing our new design it being understood that the tread design is repeated throughout the circumference of the tire, the opposite side being substantially the same as that shown;

FIG. 2 is a side elevational view thereof;

FIG. 3 is a front elevational view thereof;

FIG. 4 is an enlarged fragmentary developmental plan view of the tread design thereof; and

FIG. 5 is an enlarged cross-sectional view thereof taken along the line 5—5 of FIG. 4 in the direction indicated generally.
